The ornamental design for a spinal fusion dowel, as shown and described.

DESCRIPTION

FIG. 1 is a perspective view of a spinal fusion dowel in accordance with a preferred embodiment of the present invention.

FIG. 2 is a top plan view of the spinal fusion dowel of FIG. 1.

FIG. 3 is a bottom plan view of the spinal fusion dowel of FIG. 1.

FIG. 4 is an elevational view of a first lateral side of the spinal fusion dowel of FIG. 1.

FIG. 5 is an elevational view of a second lateral side of the spinal fusion dowel of FIG. 1.

FIG. 6 is an elevational view of a first end of the spinal fusion dowel of FIG. 1; and,

FIG. 7 is an elevational view of a second end of the spinal fusion dowel of FIG. 1.

The broken line showing forms no part of the claimed design.
